UNITED STATES PATENT OFFICE.

ASA B. HARRIS, OF VIENNA, ILLINOIS.

FOLDING BOX.

Application filed December 10, 1923. Serial No. 679,711.

To all whom it may concern:

Be it known that I, ASA B. HARRIS, a citizen of the United States, residing at Vienna, in the county of Johnson and State of Illinois, have invented a new and useful Folding Box, of which the following is a specification.

This invention aims to provide a box which may be folded up readily into small compass for shipment, novel means being provided for setting up the box and novel means being provided for reinforcing the box.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown, can be made, without departing from the spirit of the invention.

In the drawings:

Figure 1 shown in top plan, a box constructed in accordance with the invention; Figure 2 is a front elevation; Figure 3 is a section on the line 3—3 of Figure 2; Figure 4 is a section on the line 4—4 of Figure 2; Figure 5 is a plan wherein the top and the bottom are swung to open position.

The box forming the subject matter of this application comprises a top 1, a front 2, a back 3, a bottom 4 and ends 5, the terms "top," "front," "back," "bottom" and the like being selected for the purpose of describing the construction of the box, and not with a view to intimating that the box must stand in any particular position. A partition 6, is located between the ends 5. The parts 1-2-3-4-5-6 may be constructed of any light and inexpensive material, such as card-board. U-shaped reinforcing plates 7 receive the ends of the front 2 and the back 3 and are secured thereto. At their extremities, the plates 7 are provided on their inner flanges with sockets 8. U-shaped reinforcing plates 9 receive the extremities of the ends 5. The plates 9 are supplied intermediate their ends with sockets 10. The sockets 10 are located between the sockets 8 on the plates 7. Hinge plates 11 are

mounted in the sockets 10 and 8. The hinge pins 11 are secured in the sockets 10, but they rotate in the sockets 8.

Hinge plates 12 are mounted on the inner surfaces of the front 2 and the back 3. Intermediate the ends, the hinge plates 12 are equipped with sockets 14. Reinforcing plates 15 are mounted on the outer surfaces of the front 2 and the back 3. Securing elements 16 pass through the front 2 and the back 3 and engage the reinforcing plates 15 and the hinge plates 12. The hinge plates 12 and the reinforcing plates 15 are substantially coextensive in area. U-shaped hinge plates 17 receive the edges of the partition 6 and are secured thereto. The hinge pins 17 have sockets 18 disposed between the sockets 14 of the hinge plates 12 on the front 2 and the back 3. Hinge ends 19 are mounted in the sockets 18 and 14 and are secured in the sockets 14, the pins 19 being adapted to turn in the sockets 18.

End strips 20 are mounted on the outer surfaces of the top 1 and the bottom 4. Intermediate strips 21 are similarly mounted on the parts 1 and 4. The strips 20 and 21 have flanges 22 extended along the inner surfaces of the top 1 and the bottom 4, transversely thereof, as shown at Figure 5. Sockets 23 are formed in the strips 20 and 21 at the edges of the top 1 and the bottom 4. U-shaped end plates 24 straddle the upper and lower edges of the front 2 and the back 3. The plates 24 form sockets 25 located between the sockets 23. Fixed pins 26 pass through the sockets 23 and 25 and hinge top to the back 3 and hinge the bottom 4 to the front 2 along diagonally opposite edges of the box. Removable hinge pins 27 pass through the sockets 23 and 25 and connect the top 1 detachably with the front 2, the bottom 4 being detachably connected in a similar way with the back 3.

By removing the pins 27, the top 1 and the bottom 4 may be swung into open position, as shown in Figure 5, on the hinge pins 26, whereupon the back 3 may be folded against the front 2, the top 1 being turned into parallelism and the bottom 4 being turned into parallelism with the front 2, the box being thus compacted so as to occupy but little space.

Having thus described the invention, what I claim is:

A box comprising a front, a back, a top, a bottom, ends, and a partition located be-

between the ends; U-shaped hinge plates receiving the extremities of the front and the back and U-shaped hinge plates receiving the extremities of the ends, the plates of the 5 front and the back and the plates of the ends having alternating sockets, hinge pins in the sockets; reinforcing plates applied to the outer surfaces of the front and the back, hinge plates applied to the inner surfaces of 10 the front and the back, the last specified hinge plates having sockets, U-shaped hinged plates receiving the extremities of the partition and provided with sockets alternating with the sockets of the hinge 15 plates on the inner surfaces of the front and the back, hinge pins mounted in the last specified sockets, securing elements passing through the front and the back, and connecting the reinforcing plates with the hinge 20 plates on the inner surfaces of the front and the back; strips extended across the top and the bottom at the ends thereof, intermediate strips extended across the top and the bottom, the end strips and the intermediate 25 strips being provided with flanges overlap-

ping the inner surfaces of the top and the bottom, and there being sockets where the flanges join the body portions of the said strips, U-shaped strips straddled on the upper edges of the front and the back, and having sockets alternating with the sockets formed in the strips on the top and the bottom, and hinge pins passing through the sockets formed by the strips on the top and the bottom and through the sockets formed 30 in the U-shaped hinge plates on the edges of the front and the back, two of the last specified hinge pins at diagonally opposite the edges of the box being fixed and two of the last specified hinge pins at the remaining diagonally opposite edges of the box 35 being removable.

In testimony that I claim the foregoing as my own, I have hereto affixed my signature in the presence of two witnesses.

ASA B. HARRIS.
